Merchant and Kilgore

UNITED STATES PATENT OFFICE

FRANK REESE, OF MINNEAPOLIS, MINNESOTA, ASSIGNOR TO REESE METAL WEATHER STRIP CO., OF MINNEAPOLIS, MINNESOTA, A CORPORATION OF MINNESOTA

SELF-ADJUSTING INTERLOCKING WEATHERSTRIP DEVICE

Application filed May 16, 1929. Serial No. 363,475.

My invention has for its object to provide a self-adjusting interlocking weather strip device for the lock side and top of a single casement or swingable sash or for the meeting stiles and top of a double casement or swingable sash.

To the above end, generally stated, the invention consists of the novel devices and combinations of devices hereinafter described and defined in the claims.

The purpose of my invention is to provide interlocking engagement of weather strip members for hinged or swinging sashes so that shrinkage of sashes will automatically adjust the relative position of the weather strip members without strain. One member of the weather strip is yieldingly held and made of non-spring tempered metal and hence, tends to remain in position in which it is left when the sash is open, so that the members engage with very little friction when the sash is again closed. This yieldingly held member is provided with a cam-acting entrance passage arranged to be engaged by the other member and be readily drawn thereby into position if, for any reason, said yieldingly held member has been moved out of position while the sash is open.

One style of interlocking equipment now on the market for casement or hinged sash consists of rigid members without adjustment for sash shrinkage and therefore pulled loose on their nailings by shrinkage or bent out of shape through failure to engage properly in closing sash. Another style now on the market consists of one rigid member arranged to interlock with a spring tension hook member. The spring tension in combination with the interlocking engagement causes excessive friction in opening and closing the sash, making the sash hard to operate and, by constant pressure against the rigid member, loosening the rigid member on its nailing, thus permitting leakage of air between the weather strip and the sash to which it is attached.

In the accompanying drawings, which illustrate the invention, like characters indicate like parts throughout the several views.

Referring to the drawings:

Fig. 1 is a view in horizontal section showing the lock side of a casement and jamb, on an enlarged scale, and having the invention embodied therein; and

Fig. 2 is a view in horizontal section showing the meeting stiles of a pair of casements, on an enlarged scale, and having the invention embodied therein.

Referring first to the invention as shown in Fig. 1, the numeral 3 indicates the stile at the lock side of a casement hinged for horizontal swinging movement and the numeral 4 indicates a lock jamb rabbeted at 5 to receive said stile. This stile 3 at the corner formed by the outer edge and side thereof is rabbeted at 6.

The weather strip device includes a frame or jamb element or member 8 and a casement or swingable member 7. The member 7 comprises a primary U-shaped fold that affords a long narrow tongue 9 and a secondary U-shaped fold that affords a wide groove 10. These two folds are laterally spaced, reversely extended, and mounted substantially entirely within the rabbet 6. The outer side of the tongue 9 has an extension which forms an attaching flange 11 that overlaps the vertical outer edge of the stile 3 and the outer side of the fold forming the groove 10 has an outturned laterally projecting attaching flange 12 which overlaps the outer faces of the stile 11. Nails X, as shown, are provided for securing the attaching flanges 11 and 12 to the stile 3.

The member 8 is of the same general formation as the member 7 and includes a primary U-shaped fold that affords a groove 13 for the tongue 9 and a secondary U-shaped fold that affords a wide tongue 14 that is adapted to be pressed into the groove 10. The inner side of the fold forming the tongue 14 is obliquely arranged to afford a cam-acting surface 15. On the outer side of the fold forming the groove 13 is an oblique extension that affords a cam-acting surface 16 and a further extension that affords an attaching flange 17 that extends parallel to the tongue 9. This attaching flange 17 bears against the jamb 4 and is secured thereto by nails Y, only one of which is shown. On the outer

side of the tongue 14 is a laterally and inwardly projecting extension that affords a flange 18 which slidably rests on the striking face of the jamb 4 and its free longitudinal edge portion extends into a kerf 19 in said jamb.

It will be noted that the cam-acting surfaces 15 and 16 are in outwardly diverging relation the latter in advance of the former to afford a converging entrance passage for the groove 13. The frictional contact between the flange 18 and jamb 4 is such as to hold the member 8 where positioned by the member 7 during the closing of the casement. In case the member 8 is moved after the casement has been opened the tongue 9 during the closing of the casement will strike either the cam-acting surface 15 or 16 and automatically position said member 8 to receive the member 7 for interlocking engagement therewith. It will be noted that the member 7 has three point wiping contact with the member 8 and thereby forms weather-tight joints at these points between the casement and jamb. The kerf 19 prevents the leakage of water around the flange 18. The member 8 by its single attachment to the jamb 4 at the flange 17 will yield to compensate for shrinkage or warpage of the casement or jamb.

The stock from which the elements 7 and 8 are formed is relatively stiff with just sufficient spring to keep their shape. It will be noted that the transverse portions of the tongues 9 and 14 are rounded so that they will freely enter the grooves 10 and 13, respectively. The width of the entrance passage 15-16 is such that the tongue 9 will always enter the same during the closing of the casement irrespective of the amount of warpage, expansion or contraction of the casing and jamb or the distance the member 8 may be moved when said casement is open, thus making the weather strip device self-adjusting under all conditions.

The invention shown in Fig. 2 is substantially the same as that shown in Fig. 1 and is applied to the meeting stiles 20 of a pair of casements hinged for horizontal swinging movement. The only difference between the weather strip device shown in Figs. 1 and 2 is that the attaching flange 17, shown in Fig. 2, is in the form of an angle. A bearing strip 21 for the flange 18 takes the place of the striking face on the jamb 4 and is applied to the right hand casement. This bearing strip 21 is attached by nails Z to the outer face of the right hand casement and is laterally offset therefrom to leave a groove 22 between said flange and casement. The opposing faces of the meeting stiles 20 are reversely rabbed for interlocking engagement, when closed, and a rabbet 23 is formed in the left hand casement for the weather strip device.

The weather strip member in Fig. 2, might also be reversed, installing member 8 on the

left hand stile and member 7 on the right hand stile. This method of installing would bring the interlocking engagement of the two members 7 and 8 toward the center of the sashes and is therefore not the preferred installation. Water is stopped practically at the outside or weather face of the casement in the preferred installation as shown in Fig. 2.

The weather strip device for the head or top frame member for a single or double casement will be like that shown in Fig. 1. The word sash is herein used in a broad sense to cover any type of swingable member.

What I claim is:

1. A weather strip device for a pair of members, one of which is relatively stationary and the other of which is relatively swingable, said weather strip comprising a pair of self-adjusting interlocking elements applicable one to each of said members, one of said elements having a primary U-shaped fold and a secondary U-shaped fold which are laterally spaced and reversely extended, the outer side of the secondary fold having a laterally projecting flange that has sliding contact with a part on the respective member, the other of said elements being in the form of a tongue arranged to be pressed into the primary fold of the other element with a wiping contact.

2. A weather strip device for a pair of members, one of which is relatively stationary and the other of which is relatively swingable, said weather strip comprising a pair of self-adjusting interlocking elements applicable one to each of said members, one of said elements having a primary U-shaped fold and a secondary U-shaped fold which are laterally spaced and reversely extended, the outer side of the secondary fold having a laterally projecting flange that has sliding contact with a part on the respective member and extends into a kerf between said part and member.

3. The structure defined in claim 1 in which the tongue is in the form of a U-shaped fold.

4. The structure defined in claim 1 in which the outer side of the primary fold and the inner side of the secondary fold are shaped to form a converging cam-acting entrance passage for the primary fold.

5. A weather strip device for a pair of members, one of which is relatively stationary and the other of which is relatively swingable, said weather strip comprising a pair of interlocking elements applicable one to each of said members, each of said elements having a primary U-shaped fold and a secondary U-shaped fold, the folds of each element being laterally spaced and reversely extended, the primary and secondary folds of the element on the swingable member being arranged, the former to be pressed into the primary fold of the other element and the

latter to be telescoped onto the secondary fold of said other element.

6. The structure defined in claim 5 in which the outer side of the primary fold and the inner side of the secondary fold of the element for the relatively stationary member are shaped to form a converging cam-acting entrance passage for the primary fold.

7. A weather strip device for a pair of members, one of which is relatively stationary and the other of which is relatively swingable, said weather strip comprising a pair of self-adjusting interlocking elements applicable one to each of said members, each 15 of said elements having a primary U-shaped fold and a secondary U-shaped fold, the folds of each element being laterally spaced and reversely extended, the outer side of the primary fold of the element on the relatively 20 stationary member having a laterally offset attaching flange, the outer side of the secondary fold having a laterally projecting flange that has sliding contact with a part on the respective member, the outer sides of the primary and secondary folds being extended to afford attaching flanges.

8. The structure defined in claim 5 in which the folds of the two elements have three point wiping contact.

9. A weather strip device for a pair of members, one of which is relatively stationary and the other of which is relatively swingable, said weather strip comprising a pair of self-adjusting interlocking elements applicable one to each of said members, each 25 of said elements having a primary U-shaped fold and a secondary U-shaped fold, the folds of each element being laterally spaced and reversely extended, the primary and 30 secondary folds of the element on the swingable member being arranged, the former to be pressed into the primary fold of the other element and the latter to be telescoped onto the secondary fold of said other element, the 35 outer side of the primary fold and the inner side of the secondary fold of the element for the relatively stationary member being shaped to form a converging cam-acting entrance passage for the primary fold, the 40 outer side of the secondary fold of the element for the relatively stationary member having a laterally projecting flange that has sliding contact with a part on the respective member.

10. A weather strip device for a pair of members, one of which is relatively stationary and the other of which is relatively swingable, said weather strip comprising a pair of self-adjusting interlocking elements 45 applicable one to each of said members, each of said elements having a primary U-shaped fold and a secondary U-shaped fold, the folds of each element being laterally spaced and reversely extended, the primary and 50 secondary folds of the element on the swingable member being arranged, the former to be pressed into the primary fold of the other element and the latter to be telescoped onto the secondary fold of said other element, the 55 outer side of the primary fold and the inner side of the secondary fold of the element for the relatively stationary member being shaped to form a converging cam-acting entrance passage for the primary fold, the 60 outer side of the secondary fold of the element for the relatively stationary member having a laterally projecting flange that has sliding contact with a part on the respective member.

11. A weatherstrip device for a pair of members, one of which is swingable, comprising a pair of self-adjusting interlocking elements applicable one to each of said members, one of said elements being formed from a single piece of material and having a U-shaped fold with outwardly diverging side portions, said element having the fold being 65 attached at one side of its fold to the respective member and holding the fold spaced therefrom to permit lateral movement thereof, said element on the other side of its fold being loose and unattached, the other elements being in the form of a tongue arranged to be pressed into the fold, the element having the fold being formed from an inert material, whereby the tongue by its engagement with one of the outwardly diverging side portions of the fold will either push or pull the fold laterally, depending on which side of the fold is engaged by the tongue, to automatically align the fold with the tongue, the 70 inertia of the element having the fold will cause the fold to remain where positioned by the tongue when said tongue is removed therefrom.

member being arranged, the former to be pressed into the primary fold of the other element and the latter to be telescoped onto the secondary fold of said other element, the outer side of the primary fold and the inner side of the secondary fold of the element for the relatively stationary member being shaped to form a converging cam-acting entrance passage for the primary fold, the outer side of the secondary fold of the element for the relatively stationary member having a laterally projecting flange that has sliding contact with a part on the respective member, the outer side of the primary fold of the element for the relatively stationary member having a laterally offset attaching flange and the outer sides of the primary and secondary folds of the element for the swingable member each having an attaching flange.

12. A weatherstrip device for a pair of members, one of which is swingable, comprising a pair of self-adjusting interlocking elements applicable one to each of said members, one of said elements being formed from a single piece of material and having a U-shaped fold with outwardly diverging side portions, said element having the fold being 75 attached at one side of its fold to the respective member and holding the fold spaced therefrom to permit lateral movement thereof, said element on the other side of its fold being loose and unattached, the other elements being in the form of a tongue arranged to be pressed into the fold, the element having the fold being formed from an inert material, whereby the tongue by its engagement with one of the outwardly diverging side portions of the fold will either push or pull the fold laterally, depending on which side of the fold is engaged by the tongue, to automatically align the fold with the tongue, the 80 inertia of the element having the fold will cause the fold to remain where positioned by the tongue when said tongue is removed therefrom.

In testimony whereof I affix my signature.

FRANK REESE. 125
